TYPEWRITING MACHINE.

1,386,090.

Specification of Letters Patent.

Patented Aug. 2, 1921.

Application filed June 5, 1920. Serial No. 386,725.

To all whom it may concern:

Be it known that I, DANIEL A. CARPENTER, citizen of the United States, and resident of the borough of Bronx, city of New York, 5 in the county of Bronx and State of New York, have invented certain new and useful Improvements in Typewriting-Machines, of which the following is a specification.

This invention relates to improvements in escapements of typewriting machines in which force exerted by the motor spring of the carriage is transmitted to a toothed escapement wheel which it tends constantly to turn in one direction, and to which it 10 parts intermittent movements depending on the operation of a key actuated dog or pair of dogs with which the teeth of the wheel coact. The object of the invention, generally stated, is to improve the operation and 15 increase the number of good qualities of such escapements. The invention consists of an escapement comprising the mechanism which is hereinafter described and specified in the claims, and the novel features of which 20 pertain mainly to the construction and operation of the stepping or snapping dog, and to the combination with it of a dog rocking device and a shock absorbing device.

In the accompanying drawings, of which 25 there are three sheets on which like reference numerals designate like parts of different views:

Figure 1 is a rear sectional elevation of an escapement in which features of the invention are embodied, and of a fragment of the framework of a typewriting machine which includes the escapement, the sectional plane being indicated by the line 1-1, Fig. 2;

Fig. 2, a side elevation of the same, and some other mechanism, and of a fragment, partly in section, of the framework, a cross section of the carriage rack being also shown;

Fig. 3, a sectional plan on the plane 3-3, Fig. 1, of parts of the mechanism, including the escapement wheel and adjacent devices;

Fig. 4, a sectional plan on the planes 4-4, Fig. 1, showing the snapping dog and fragments of the escapement wheel and dog-supporting devices;

Fig. 5, a perspective of the dogs and coacting devices, separated from the rest of the machine;

Fig. 6, a front face view of a part and of a fragment of another part of the mechanism represented by Fig. 5;

Fig. 7, a sectional plan on the plane 7-7, Fig. 1, of features illustrated in perspective in Fig. 5 and in rear and side elevation in Figs. 1 and 2, respectively;

Fig. 8, a fragmental rear elevation illustrating a modification which includes a shock absorbing stop device;

Fig. 9, a side and sectional elevation of parts of this modification;

Fig. 10, a fragmental and sectional plan of parts of this modification, combined with a slide which forms a dog rocking and carriage releasing device, and with tabulator 70 stop-levers which act on and operate the slide;

Fig. 11, a fragmental side and sectional elevation of parts of this escapement and tabulator;

Fig. 12, a fragmental side and sectional elevation of an escapement which includes the snapping dog illustrated in Figs. 1 to 7, inclusive, a holding dog, and a dog rocking device carrying stops, but does not include 80 a slide which forms part of the dog rocking device illustrated in those figures;

Fig. 13, a rear elevation of the holding dog and fragments of the dog rocking device, snapping dog and escapement wheel, of the 85 escapement represented by Fig. 12;

Fig. 14, a plan of the holding dog and dog rocking device which form parts of the last mentioned escapement;

Fig. 15, a side and sectional elevation of 90 parts of an escapement, together with a fragment of framework, which escapement contains modifications of some of the features shown in other views above mentioned; and

Fig. 16, a sectional plan of that part of the mechanism which is shown in Fig. 15 below the line 16-16.

The invention may be applied to typewriting machines of many forms. The particular machine in which it is shown is a Remington deprived of part of its escapement mechanism. It includes a universal bar which is movable by the type bars toward the back of the machine and which 100 usually is connected to a downwardly extending arm of a dog rocker. In the operation of the machine the lower end of this

arm is moved by the action of the universal bar toward the back of the machine. Such a universal bar connected to the dog rocker of an escapement is illustrated and described in Patent No. 1,289,934, granted Dec. 31, 1918, for an invention made by George A. Seib.

In the above mentioned Remington machine the motor spring of the carriage transmits force to a toothed escapement wheel 1 (Figs. 1 and 2) which it tends constantly to turn in the direction indicated by the curved arrow (Fig. 1). This force acts through the rack bar 2, pinion 3, sleeve 4, ratchet wheel 5 and pawl 6, on the hub 7 of the escapement wheel, the pawl being mounted at the front of the hub on the pin 8 (Fig. 1) which is fixed in and projects from the hub, and being under spring pressure exerted by the spring 9 (Fig. 3) attached to the hub. The rack bar is attached to the carriage, the pinion is fast on the sleeve, and the sleeve and ratchet wheel are parts of one piece of stock. The pawl engages inner faces of the ratchet teeth, which also have outer faces intended to be engaged by a back spacing pawl (not shown herein). The escapement wheel includes the spider 10 on which are the teeth 11 and which is attached to the hub 7 by the screws 12. The hollow screw plug 13 having the head 14 extends through the hub 7 which has an internal thread engaged with the thread of the plug, the parts being screwed together so that the head 14 of the plug is in contact with the front of the hub. At the rear end of the sleeve 4 is a bearing ring 15 (Fig. 3) which fits tightly in the sleeve. The shaft 16 extends through the pinion 3, sleeve 4, bearing ring 15, and plug 13 and is supported at its ends in bearings held by or formed in the blocks 17 and 18 which are parts of the bracket 19 mounted on and fastened to the top plate 20 of the machine. The pinion, sleeve 4 and ratchet may rotate while the shaft 16 is at rest, but the escapement wheel together with the plug 13 is affixed to the shaft 16 by the set screws 21, so that when this wheel rotates it turns on the bearings of the shaft. The ratchet 5 and pawl 6 are similar in form, arrangement and action to a ratchet and pawl shown and described, and numbered 63 and 78 respectively, in the application of Oscar Woodward, Serial No. 300,571, filed May 29, 1919.

The dog rocker which this machine contained, and in place of which novel dog rocking devices of different forms are shown herein, was mounted on the pivots 22 (Figs. 1 and 2), extending through the blocks 23 and made fast therein by the set screws 24, these blocks being part of the support 25 carried by the top plate 20.

All of the above mentioned parts of the machine which are designated by the refer-

ence numeral 1 *et seq.* to 25, inclusive, were invented or devised by others.

The escapement which is illustrated in Figs. 1 to 7, inclusive, and which embodies many of the features of the invention herein claimed, includes both a snapping dog and a holding dog. It so operates as to allow the carriage to step only when the actuated key moves upward, but the holding dog may be so adjusted as to render it temporarily functionless, and when that is done, or when the holding dog is detached from its support, the rest of the mechanism constitutes a reverse escapement which allows the carriage to step, or begin to step, before the depressed key moves upward. Whether the holding dog is adjusted as above indicated or not, the escapement comprises the combination with the toothed-wheel or escapement wheel, which the carriage spring tends constantly to turn, of a dog carrier, a snapping dog, two stops and a key actuated dog rocking device. These elements are shown in their preferred forms in Figs. 1 to 7, inclusive.

The dog carrier is mounted on a bearing on which it is angularly movable and which is co-axial with the escapement wheel. The hub 7 of the wheel forms the bearing shown. This bearing consists of the short cylinder 26, behind the small flange 27 (Figs. 2 and 3) formed on the hub at its front end. The dog carrier is the device which is shown in Fig. 5 and of which the ring 28 is a part. The ring 28 surrounds the bearing 26 and is confined between the flange 27 and spider 10 of the escapement wheel, the ring being loosely mounted on the bearing. At one side of the ring 28 is an arm bent in four places, as appears by Fig. 5 and other figures. It is composed of the parts 29, 30, 31, 32 and 33, the part 31 having on it the projection 34 (Fig. 6), not fully shown in Fig. 5. The parts 32 and 33 form ears which are in alignment and perforated. The parts 30, 31 and the ears are farther from the axis of the ring 28 than the outer ends of the teeth of the escapement wheel are from the axis of the wheel, and when the dog carrier is mounted on its bearing the ears 32 and 33 extend across the space which is included between the planes of the faces of the spider 10, and the perforations in the ears are close to the plane of the front face of the spider (Figs. 2 and 3). The spring 35 connected to the projection 34 and to the top plate (Fig. 1) tends constantly to turn the dog carrier from its normal position in the direction opposite to that in which the wheel steps.

The snapping dog 36 (Fig. 5) is attached to or formed on a supporting arm bent as shown and composed of the parts 37, 38, 39, 40 and 41 (Figs. 3-6) of which 40 and 41 are perforated ears which fit between the ears 32 and 33 of the dog carrier. This arm

is pivotally attached to the dog carrier by the pin 42 which passes through the perforations in the ears of the dog carrier and arm and on which is the coiled spring 43 which acts against the parts 31 and 39. The dog supporting arm is movable on its own pivotal axis, which is that of the pin 42, to change its position with relation to that of the dog carrier. When it is in one position the part 37, which overlaps the front face of the ring 28, is in contact with the ring. The spring 43 tends to keep the arm at rest on its own pivotal axis by pressing the arm against the ring, but the arm and dog carrier are movable together on their common axis, which is that of the wheel, whether the arm is in contact with the ring or not. The arm is movable from the ring, on the axis of the pin 42, by force that is great enough to overcome that of the spring 43.

The elongation 44 forming part of the elongated and curved dog shown (see Figs. 1, 4 and 5) has no function except when the carriage is driven or pushed toward the right while the carriage rack is engaged with the escapement pinion. If this feature of the invention should be omitted the feeding operation of the mechanism would not be affected. The length and depth of the elongation 44 are such as to cause it slightly to overlap and extend close to the back of the tooth next in front of the dog (36) when the dog is engaged with the wheel, and the inner surface 45 (Fig. 5) of the elongated dog should be curved, the axis of curvature being that of the wheel. The appendage 46, formed on or rigidly attached to the dog and extending farther from the axis of the wheel than do the teeth, has functions which depend on the coaction of the dog rocking device and stops with this appendage and which can best be clearly explained after said device and stops shall have been described.

The arrangement of the dog carrier, dog supporting arm and dog are such that the dog may extend into the path of the teeth of the wheel and may be moved out of that path by rocking the dog supporting arm on its own pivotal axis. That pivotal axis is in a plane to which the axis of the wheel is perpendicular, at a point on one side of said pivotal axis, and the teeth engaging face of the dog shown is at the same or approximately the same distance as is said point, from said pivotal axis. Preferably the teeth engaging face of the dog is part of the surface of a cylinder, the axis of which coincides with the pivotal axis of the dog, and to which the plane parallel to that axis and containing the axis of the wheel is tangent, the faces of the teeth of the wheel being also slightly curved to fit them to the face of the dog. It is evident therefore that the normal positions of the dog carrier and

dog may be such as to enable the dog to engage a tooth of the wheel either directly under the axis of the wheel or on one side or the other of a vertical plane containing that axis. Their preferred normal positions, especially when the invention is applied to a Remington machine, are those in which they are shown herein, and in which they are fitted to coact with an angularly movable dog rocking device which may replace the Remington dog rocker, and be mounted on its supporting pivots 22. When the dog is in the normal position indicated by each figure in which the dog is shown, it is engaged with a tooth of the wheel and the wheel prevents the spring 35 from turning the dog and dog carrier on the axis of the wheel.

The two stops above mentioned are arranged to limit angular movements of the dog carrier and dog 36 on their common axis, *i.e.*, the axis of the wheel. These stops and the dog rocking device are united when that device has the form shown in Figs. 1, 2, 5 and 7, but the stops may be attached to or united with some other part of the machine, as hereinafter explained. This particular dog rocking device comprises the shaft-like hub 47, upper and lower main arms 48 and 49, and rear arm 50, shorter than arm 48, the hub and these arms being a single forging or casting. The hub is mounted on the pivot pins 22 on which the device may rock as did the Remington dog rocker which it replaces, and the lower arm 49 is connected with the universal bar by means including the link 51, the rear part only of which is shown (Figs. 1 and 2). At the upper end of the arm 48 are stops 52 and 53, projecting upward from the enlargement 54, different views of the upper part of this arm, including the enlargement and stops, being shown in Figs. 1, 2, 5 and 7. The top faces of the stops are close to but a little below the path of the teeth of the escapement wheel, and between these stops the appendage 46 of the dog 36 extends, the body of the dog being over the stops. When the dog rocking device is in its normal position, in which it is shown, the stops extend past the appendage 46 toward the front of the machine, far enough to enable the dog 36 to rock out of engagement with the wheel without carrying the appendage from between the stops. The distance between the stops is great enough to leave a space between the appendage and the stop 53 when the appendage is in contact with the stop 52, but the space may be some narrower or much wider than the drawings show it, although the width must not be great enough to allow the dog to snap past more than one tooth of the wheel at a time. The angular plate composed of parts 55 and 56 is attached to the back of the enlargement 54 by 130

screws 57 passing loosely through slots in the part 55, the plate being a slide, prevented by the heads of the screws from moving backward from its support 54 but movable in the direction of its own length on the stems of the screws. The spring 58 connected to it and to the pin 59 fixed in the arm 48 tends to keep the slide in that relation to its support in which it is shown. 10 The part 56 of this slide passes loosely through an open slot in the stop 52 and normally extends from it toward the stop 53 and behind and close to the appendage 46, but between the stop 53 and the shoulder 60 formed by this part of the slide is a space 15 61 (Fig. 7) wide enough to allow the appendage 46 to pass into it. This slide forms part of the dog-rocking device.

The holding dog 62 is formed on or fastened to the arm 63 at its upper end and this arm is attached to the arm 50 of the dog rocking device by the screws 64 and 65. The screw 64 passes through the slot 66 cut in the arm 63 as indicated by the dotted outline shown in Fig. 2. If the screws 64 and 20 65 are loosened the arm 63 may be turned on the axis of the screw 65, so that the holding dog may be adjusted at any desired distance from the dog 36. When the holding 25 dog is turned backward as far as it will go it will not be rocked into the path of the teeth of the wheel as the dog rocking device is actuated by the universal bar. The spring 67 indicated by dotted lines in Fig. 2 and 30 68 extending from a pin fixed in the framework to the arm 49 of the dog rocking device, is the restoring spring of that device.

The action of the escapement constructed as described and used when the holding dog 40 is adjusted so as to enable it to coact with the other parts resembles generally, and in some but not all respects particularly, that of a common escapement comprising a holding dog and a stepping dog. When the dog 45 rocking device is in its normal position, shown in Fig. 2, the dog 36 is engaged by a tooth of the wheel and the appendage 46 is in contact with the stop 52, the wheel being held so as to prevent the carriage spring 50 from turning it, by the joint action of the stop, appendage, and body of the dog 36 on 55 the engaged tooth. As the universal bar is actuated, on the depression of a printing key, backward motion is imparted to the link 51 and thence to the lower end of arm 49 of the dog rocking device, so that holding dog 62 and slide 55—56 together with stops 52 and 53 are carried forward, or toward the front of the machine. The slide, acting on 60 appendage 46, pushes it forward as indicated by dotted lines in Fig. 7 and thus forces the dog 36 to turn on pin 42 and to pass out of the path of the engaged tooth as indicated by dotted lines in Fig. 4, but before the dog 36 65 clears that tooth the holding dog gets in its

path, and at the end of the downward movement of the key the wheel is held by the holding dog. Instantly after dog 36 clears the tooth, spring 35 turns the dog carrier and that dog on bearing 26 until appendage 70 46 meets stop 53, further motion of the dog carrier and dog 36 on said bearing being prevented by the joint action of stop 53, the appendage, and the body and supporting arm of dog 36, on the dog carrier. As the 75 appendage 46 passes from in front of part 56 of the slide, spring 43, acting through the dog supporting arm, presses dog 36 against the front side of the tooth which the holding dog then engages, and there dog 80 36 stays as long as the holding dog continues to prevent the wheel from turning. When the printing key moves upward the dog rocking device impelled by its restoring spring returns to its normal position, carrying the holding dog backward and out of the path of the engaged tooth. As soon as the tooth is released the wheel turns and then dog 36, impelled by spring 43, snaps behind the receding tooth, and the next advancing 90 tooth meets dog 36 and pushes it back to its normal position where it is arrested and forced to stop the wheel, appendage 46 then being again in contact with stop 52.

If dog 62 is adjusted so that it will not be 95 carried into the path of the teeth of the wheel, then the dog rocking device, on the depression of a printing key, disengages dog 36 from the wheel through the action of part 56 of the slide on appendage 46 as above explained, whereupon the wheel, released at the end of the downward movement of the key, begins to turn and simultaneously dog 36 snaps in the direction opposite to that in which the wheel turns. Should the key not 100 be held down at all the dog 36, having turned on the axis of the wheel until appendage 46 is in contact with stop 53, will enter the path of the approaching tooth as the wheel turns, and be forced back to its normal position 110 by that tooth. The appendage 46 will not touch the slide after it passes from it to stop 53, during the snapping action of the dog, provided the return movement of the rocking device is quick enough to withdraw 115 the part 56 of the slide from the path of the appendage. If, however, the key should be held down, the appendage 46 enters the space 61 (Fig. 7) as the dog moves into the path of the advancing tooth, and unless the 120 part 56 of the slide is withdrawn from the path of the appendage before the tooth acts on the dog, the appendage is forced against the shoulder 60 and pushes the slide along, stretching the spring 67, until the shoulder 125 is even with and the appendage in contact with the working face of the stop 52, when the dog and wheel are arrested as before explained. On the return of the dog rocking device to its normal position the slide, which 130

is then carried backward, is released from the appendage and then is drawn lengthwise by the spring 67 so that part 56 is restored to its former position behind the appendage.

5 It will be seen that shoulder 60 is useful merely to insure proper action of the reverse escapement should a printing key be held down for a moment or longer, and that if part 56 of the slide were large enough to 10 close the space 61 the action of the snapping dog would not be affected at all when the holding dog also is used, and would not be so much affected when the holding dog is not used as greatly to trouble highly skilled operators of machines which contain reverse escapements, since such operators seldom if ever hold keys down. If the space 61 were to be closed by part 56 of the angular plate forming the described slide, of course the 15 plate would not then act as a slide, and might be made fast to the part 56 of the dog rocking device. Then the whole function of the plate would be to push the dog out of engagement with the wheel as above explained.

Since dog 36 does not change its position with relation to the tooth which engages it as the wheel steps, of course then the faces of the dog and tooth are not subjected to 20 wear from being rubbed together.

Although the ratchet and pawl (5 and 6) above described enable the escapement wheel to be kept at rest, when the carriage is retracted to allow line after line to be written, 25 yet unless special means is provided to overcome friction then tending to turn the wheel backward, it will sometimes so turn enough to carry the engaged tooth away from the dog as far as the tooth advances in a letter spacing movement, the result being that 30 there is lost motion to be absorbed before the tooth and dog can again coact in holding the carriage. This lost motion plus similar lost motion due to the retraction of the pawl 35 from a tooth of the ratchet, is liable to amount to enough to allow the carriage to travel more than a full letter space distance. Hence, although the carriage may be arrested 40 at the proper position by the margin stops, nevertheless it may thereafter advance a letter space distance before it will be held by 45 the escapement, and when it does so advance and writing is immediately begun the first letter of a line is written at a letter 50 space distance from its proper position. The function of the elongation 44 of dog 36 is to overcome the friction above referred to and thus prevent the movement of the engaged tooth of the wheel away from the dog 55 under the conditions explained. This elongation forms a stop with which the back of a tooth is brought in contact as it begins to move backward and which, although it will yield to force great enough to turn the dog 60 on pin 42, is nevertheless effective to prevent

the aforesaid friction from turning the wheel backward.

It is feasible to dispense with the ratchet and pawl, and were that to be done it would affect the utility of elongation 44 of dog 36. 70 Let it be supposed that the ratchet 5 is fast on the hub 7 of the escapement wheel so that pinion 3, the ratchet, the escapement wheel and shaft 16 would all be forced to rotate as a unit on the bearings of the shaft, as well 75 when the carriage rack, engaging the pinion, moves to the right as when it moves to the left. Then if the carriage should be drawn by the line spacing lever or forced by the back spacing pawl acting on the external 80 faces of the teeth of ratchet 5, to travel toward the right, dog 36 would be turned on pin 42 by the action of a tooth or teeth of the escapement wheel on the rear face of the dog, each tooth acting on the dog as a tooth 85 of a backwardly turning ratchet wheel acts on a pawl, and the escapement wheel would turn to the required extent, and be reengaged by the dog at the end of the movement. The escapement would perform not 90 only the functions peculiar to escapements but also those of the ratchet and pawl, and the lost motion which would result from its whole action would be that and that only which would result from its action either as 95 an escapement or as a ratchet and pawl.

The curvature, coaxial with the wheel, of the inner surface of the elongated dog fits the elongation both to resist backward motion of the wheel and to coact with the teeth 100 when the dog is turned by them on pin 42, as described.

The modification which is partly shown in Figs. 8 and 9 is the same in construction as the escapement illustrated in Figs. 1-7, 105 inclusive, except in respect of the dog rocking device and what is mounted on it. The dog rocking device of this modification includes the shaft-like hub 47, lower arm 49 and rear arm 50, corresponding to parts 110 designated by those numerals respectively, of the above described dog rocking device. The hub 47 of this modified device is to be mounted on the pivots 22, and its arm 49 is to be connected to the link 51. The upper 115 front arm 68, (Fig. 9) has at the top an enlargement or head 69, and to the back of this head the plate 70 is attached by the screws 71 passing loosely through the slots 72 in the plate. The body of the plate is held close 120 to the head 69 by the heads of the screws but the plate is movable a little in the direction of its length on the screws as guides. The parts 83 and 74 of this plate, a top view of which is shown in Fig. 10, extend over the 125 head 69, the metal being bent as indicated, especially in Fig. 9, and between them passes the appendage 46 of the dog 36. These parts of the plate correspond to and have the functions of the stops 52 and 53 formed on 130

the arm 48 of the dog rocking device heretofore described, the body of the plate being close to appendage 46 and the latter being normally held against stop 73 by the action 5 of a tooth of the escapement wheel on dog 36. The spring 75 which extends from this stop plate to the frame, or a rigid projection formed on or attached to it, such as the fixed pin 76, prevents the stop plate from 10 being pushed toward the right side of the machine by the action of appendage 46 on stop 73, except perhaps to a very slight extent at the instant when the appendage is driven against the stop by the wheel as it 15 makes a stepping movement. The strength of the spring is such as to compel the stop plate instantly to return to its normal position if it should be thus slightly forced from it, and may be great enough to prevent the 20 stop plate from being moved perceptibly by force transmitted to it from the wheel.

The holding dog 62 of this modification has the supporting arm 77 which is attached to rear arm 50 of the dog rocking device by 25 screws 64 and 65. The peculiar shape of arm 77 and the oblong opening 78 in the stop plate 70 enable the carriage releasing slide shown in Figs. 10 and 11 to be used, as will be explained.

30 In the operation of this modification the dog 36 is forced from the wheel by the action of the body of the stop plate on the appendage 46, and dog 62, dog 36, the dog carrier and the wheel act and coact as above described, while the stops 73 and 74 perform the functions of stops 52 and 53. As the shock at the arrest of the carriage is taken by spring 75, and by it absorbed or partly absorbed and partly transmitted to the 35 frame, the carriage is arrested with but little noise. It will be seen that the force transmitted to the stop device by the wheel does not so act on the dog rocking device of which the stop device is a part as to subject 40 the pivot at the right end of hub 47 of the dog rocking device to a sharp blow. The right pivot of a common dog rocker is subjected to such a blow each time the carriage 45 steps and that makes the escapement 50 taining the dog rocker quite noisy.

The dog 36 may be forced out of engagement with the escapement wheel by means of a slide as well as by an angularly movable dog rocking device. This will be readily understood from the foregoing description and a brief explanation of what is shown in Figs. 10 and 11. The form of escapement illustrated in these figures is that represented in Figs. 8 and 9, but Figs. 10 and 11 also 55 show a portion of a tabulator such as is used in Remington machines. In the tabulator frame 79, attached to the top plate 20 and other parts of the framework of the machine, the tabulator levers 80 are mounted 60 on the fulcrum rod 81 fixed in the tabulator 65

frame, the upper ends of the levers being movable toward the front of the machine when the tabulator keys are actuated. The dog rocking and carriage releasing slide 82 having backwardly extending arms 83 is 70 attached by screws 84 to inner faces of the tabulator frame, the screws passing loosely through slots 85 in the arms 83. The edge 86 of the slide is close to the tabulator levers when the slide and levers are in their normal 75 positions, and the springs 87 attached to the slide and frame 79 exert a backward pull on the slide. This slide passes on one side of and in front of the dog supporting arm 77 and into opening 78 in the stop plate 70. 80 When a tabulator key is actuated slide 82 is pushed by the tabulator lever through opening 78 and against appendage 46 of dog 36 and forces the dog forward until the wheel is released. When the carriage is arrested 85 by the tabulator stops and the tabulator lever returns to its normal position, dog 36 reengages the wheel as before explained and slide 82 is drawn back to its normal position by the springs 87. As will be seen, this 90 slide does not interfere with the operation of the escapement, the length of slot 78 in stop plate 70 being greater than the width of the slide at its front end, and arm 77 being movable to carry dog 62 into the path of 95 the teeth of the wheel although the slide extends in front of that arm.

The particular escapement represented by Figs. 12-14, inclusive, comprises an angularly movable dog rocking device having the 100 hub 47, lower arm 49 and upper arm 88 on which is the head 89. In the head is the recess 90 (Fig. 14), open at the top and front of the head. Two walls of this recess form the stops 91, 92 which have the functions of stops 52 and 53, and the back wall 93 of the recess extends behind and close to appendage 46 of dog 36, and acts on the appendage in the operation of the machine to force dog 36 out of engagement with the 110 wheel, as does the body of stop plate 70. The holding dog 94 is affixed by screws 95 to the back of the head 89. This dog rocking device is to be mounted on the pivot pins 115 22 and to it link 51 is to be connected. The rest of this escapement is composed of parts 120 that have been described. Its operation will be understood, it is believed, without further explanation.

In Figs. 15 and 16 are shown stops which 120 are attached to the framework of the machine and which act to limit the angular movements of dog 36 and the dog carrier on the axis of the wheel. These stops 96 and 97 are parts of a bent plate which is fastened by screws 98 to the part 25 of the framework. Appendage 46 of dog 36 extends between these stops, and the front end of the finger 99, fastened to the arm 100 of the dog rocking device by screws 101, is 130

behind and close to the appendage, the holding dog 102 being on arm 100 at its upper end. This dog rocking device comprises also the hub 47 and lower arm 49, and when 5 it is put into the machine it is mounted on the pivot pins 22 so that the hub is supported by them at its ends, and link 51 is connected to the lower end of arm 49. The other parts of this escapement are the dog 10 carrier, stepping dog and toothed wheel above described. As the upper end of arm 100 moves forward, impelled by the action 10 of link 51 on arm 49, finger 99 pushes appendage 46 before it until dog 36 clears the 15 engaged tooth of the wheel. Then, the wheel being held by dog 102, the dog carrier and dog 36 turn on their common axis, appendage 46 is carried to and against stop 97, and thereafter dog 36 re-enters the path of the 20 teeth of the wheel and is restored to its normal position as the wheel steps when it is released from dog 102, retracted from it by the restoring spring of the dog rocking device. The joint action of stop 96, appendage 25 46 and body of dog 36, in stopping and holding the wheel at the end of a stepping movement, is the same as that of stop 52 and the appendage and body of the dog. It will be seen therefore that stops, which 30 mechanism embodying the invention may include, might be attached to or formed on a fixed part of the machine, instead of the dog rocking device.

What I claim as new and desire to secure 35 by Letters Patent, is:—

1. In an escapement comprising a toothed wheel and means tending constantly to turn it in one direction, the combination with the wheel of an angularly movable dog carrier, a dog, two stops, and a key actuated 40 dog rocking device, the dog carrier being mounted on a bearing that is co-axial with the wheel and being subjected to stress from a spring that tends constantly to turn it in 45 the direction opposite to that in which the wheel steps, the dog being supported by the dog carrier and having a distinct pivotal axis and being subjected to stress from a spring which tends to keep the dog at rest 50 on its own pivotal axis, the stops being arranged to limit angular movements of the dog carrier and dog on said bearing, and the dog rocking device being arranged to act on the dog so as to turn it on its own pivotal axis.

2. In an escapement comprising a toothed wheel and means tending constantly to turn it in one direction, the combination with the wheel of an angularly movable dog carrier, a dog and arm and pair of ears all fast together, a pivot pin, two stops, and a key actuated dog rocking device, the dog carrier 60 forming a ring and pair of ears and being mounted on a bearing that extends through 65 said ring and is coaxial with the wheel and

being subjected to stress from a spring that tends constantly to turn it in the direction opposite to that in which the wheel steps, the dog being supported by said arm and first mentioned pair of ears and being pivotally secured to the dog carrier by said pivot pin, which extends through said two pairs of ears, and being subjected to stress from a spring which tends to keep the dog at rest on said pivot pin, the stops being arranged to limit angular movements of the dog carrier and dog on said bearing, and the dog rocking device being arranged to act on the dog so as to turn it on said pivot pin.

3. In an escapement comprising a toothed wheel and means tending constantly to turn it in one direction, the combination with the wheel of an angularly movable dog carrier, a dog and arm and pair of ears fast together, a pivot pin, a coiled spring, two stops, and a key actuated dog rocking device, the dog carrier forming a ring and pair of ears and being mounted on a bearing that extends through said ring and is coaxial with the wheel and being subjected to stress from a spring that tends constantly to turn it in the direction opposite to that in which the wheel steps, the dog being supported by said arm and first mentioned pair of ears and being pivotally secured to the dog carrier by said pivot pin, which extends through said two pairs of ears and being subjected to stress from said coiled spring, which surrounds said pivot pin, the dog carrier and said arm being face to face and the arm being normally held by the spring against the dog carrier, the stops being arranged to limit angular movements of the dog carrier and dog on said bearing, and the dog rocking device being arranged to act on the dog so as to turn it on said pivot pin.

4. In an escapement comprising a toothed wheel and means tending constantly to turn it in one direction, the combination with the wheel of an angularly movable dog carrier, a dog and arm fast together, two stops, and a key actuated dog rocking device, the dog carrier being at the front of the wheel and subjected to stress from a spring that tends constantly to turn it in the direction opposite to that in which the wheel steps and its bearing being coaxial with the wheel, said arm being pivotally connected to the dog carrier and the dog projecting rearwardly from said arm and being subjected to stress from a spring which tends to keep the dog at rest on its own pivotal axis, the stops being arranged to limit angular movements of the dog carrier and dog on said bearing, and the dog rocking device being arranged to act on the dog so as to turn it on its own pivotal axis.

5. In an escapement comprising a toothed wheel and means tending constantly to turn

it in one direction, the combination with the wheel of an angularly movable dog carrier, a dog and arm fast together, two stops, and a key actuated dog rocking device, the dog carrier being at the front of the wheel and subjected to stress from a spring that tends constantly to turn it in the direction opposite to that in which the wheel steps and its bearing being coaxial with the wheel, said 5 arm being pivotally connected to the dog carrier and extending across part of the front face of the dog carrier and the dog projecting rearwardly from said arm and dog carrier and the arm and dog being subjected to stress from a spring which tends 10 to hold the arm against the dog carrier, the stops being arranged to limit angular movements of the dog carrier and dog on said bearing, and the dog rocking device being 15 arranged to act on the dog so as to turn it 20 on its own pivotal axis.

6. In an escapement comprising a toothed wheel and means tending constantly to turn it in one direction, the combination with the 25 wheel of an angularly movable dog carrier, a dog and an elongation thereof fast together, two stops, and a key actuated dog rocking device, the dog carrier being mounted on a bearing that is coaxial with the wheel 30 and being subjected to stress from a spring that tends constantly to turn it in the direction opposite to that in which the wheel steps, the dog being supported by the dog carrier and having a distinct pivotal axis 35 and being subjected to stress from a spring which tends to keep the dog at rest on its own pivotal axis, and the elongation of the dog extending nearly to and overlapping the back of the first tooth behind which the dog 40 rests when it is fully engaged by the wheel, the stops being arranged to limit angular movements of the dog carrier and dog on said bearing, and the dog rocking device being 45 arranged to act on the dog so as to turn it on its own pivotal axis.

7. In an escapement comprising a toothed wheel and means tending constantly to turn it in one direction, the combination with the wheel of an angularly movable dog carrier, a dog and an elongation thereof fast together, two stops, and a key actuated dog rocking device, the dog carrier being mounted on a bearing that is coaxial with the wheel and being subjected to stress from a 50 spring that tends constantly to turn it in the direction opposite to that in which the wheel steps, the dog being supported by the dog carrier and having a distinct pivotal axis and being subjected to stress from a 55 spring which tends to keep the dog at rest on its own pivotal axis and the elongation of the dog extending nearly to and overlapping the back of the first tooth behind which the dog rests when it is fully engaged by the 60 wheel and having a cylindrical inner sur- 65

face co-axial with the wheel, the stops being arranged to limit angular movements of the dog carrier and dog on said bearing, and the dog rocking device being arranged to act on the dog so as to turn it on its own pivotal 70 axis.

8. In an escapement comprising a toothed wheel and means tending constantly to turn it in one direction, the combination with the wheel of an angularly movable dog carrier, a dog, two stops, and a key actuated dog rocking device, the dog carrier being mounted on a bearing that is coaxial with the wheel and being subjected to stress from a spring that tends constantly to turn it in 75 the direction opposite to that in which the wheel steps, the dog being supported by the dog carrier and having a distinct pivotal axis and being subjected to stress from a spring which tends to keep the dog at rest 80 on its own pivotal axis, the bearing of the dog on this axis being farther from the axis of the wheel than are the outer ends of the teeth of the wheel and being bisected by a plane which is perpendicular to the axis 85 of the wheel and close to that part of the wheel from which the teeth spring, the stops being arranged to limit angular movements 90 of the dog carrier and dog on said first mentioned bearing, and the dog rocking device being arranged to act on the dog so as to turn it on its own pivotal axis.

9. In an escapement comprising a toothed wheel and means tending constantly to turn it in one direction, the combination with the wheel of an angularly movable dog carrier, a dog and an appendage fast together, two stops, and a key actuated dog rocking device, the dog carrier being mounted on a bearing that is coaxial with the wheel and being subjected to stress from a spring that tends constantly to turn it in the direction opposite to that in which the wheel steps, the dog being supported by the dog carrier and having a distinct pivotal axis and being subjected to stress from a spring which tends to keep the dog at rest on its own pivotal axis, and the appendage of the dog extending farther from the axis of the wheel than do the teeth, the stops being arranged 100 to limit angular movements of the dog carrier and dog on said bearing, one of the stops being subject to contact with said appendage so as to enable the wheel to be arrested and held by the joint action of this stop and the 105 appendage and body of the dog, and the dog rocking device being arranged to act on the dog so as to turn it on its own pivotal axis.

10. In an escapement comprising a toothed wheel and means tending constantly to turn it in one direction, the combination with the wheel of an angularly movable dog carrier, a dog and an appendage fast together, two stops, and a key actuated dog rocking device, the dog carrier being mounted on a 110

- bearing that is coaxial with the wheel and being subjected to stress from a spring that tends constantly to turn it in the direction opposite to that in which the wheel steps, 5 the dog being supported by the dog carrier and having a distinct pivotal axis and being subjected to stress from a spring which tends to keep the dog at rest on its own pivotal axis and the appendage of the dog 10 extending farther from the axis of the wheel than do the teeth, one of the stops being subject to contact with said appendage so as to enable the wheel to be arrested and held by the joint action of this stop and the appendage and body of the dog, the other stop being subject to contact with said appendage to enable the snapping movement of the dog to be limited by the joint action of this stop and the appendage, and the dog 15 20 25 30 35 40 45 50 55 60 65
- rocking device being arranged to act on the dog so as to turn it on its own pivotal axis.
11. In an escapement comprising a toothed wheel and means tending constantly to turn it in one direction, the combination with the wheel of an angularly movable dog carrier, a dog, two stops, and a key actuated dog rocking device including a rocking arm, the dog carrier being mounted on a bearing that is co-axial with the wheel and being subjected to stress from a spring that tends constantly to turn it in the direction opposite to that in which the wheel steps, the dog being supported by the dog carrier and having a distinct pivotal axis and being subjected to stress from a spring which tends to keep the dog at rest on its own pivotal axis, the stops being on said rocking arm and arranged to limit angular movements of the dog carrier and dog on said bearing, and the dog rocking device being arranged to act through said rocking arm on the dog so as to turn it on its own pivotal axis.
12. In an escapement comprising a toothed wheel and means tending constantly to turn it in one direction, the combination with the wheel of an angularly movable dog carrier, a dog and an appendage fast together, two stops, and a key actuated dog rocking device including a rocking arm, the dog carrier being mounted on a bearing that is coaxial with the wheel and being subjected to stress from a spring that tends constantly to turn it in the direction opposite to that in which the wheel steps, the dog being supported by the dog carrier and having a distinct pivotal axis and being subjected to stress from a spring which tends to keep the dog at rest on its own pivotal axis, and the appendage of the dog extending farther from the axis of the wheel than do the teeth, the stops being arranged to limit angular movements of the dog carrier and dog on said bearing, one of the stops being on said rocking arm and subject to contact with 130
- the appendage so as to enable the wheel to be arrested and held by the joint action of the stop and the appendage and body of the dog, and the dog rocking device being arranged to act through said rocking arm on the dog so as to turn it on its own pivotal axis.
13. In an escapement comprising a toothed wheel and means tending constantly to turn it in one direction, the combination with the wheel of an angularly movable dog carrier, a dog and an appendage fast together, two stops, a shock absorbing spring, and a key actuated dog rocking device, the dog carrier being mounted on a bearing that is coaxial with the wheel and being subjected to stress from a spring which tends to keep the dog at rest on its own pivotal axis, and the appendage of the dog extending farther from the axis of the wheel than do the teeth, the stops being arranged to limit angular movements of the dog carrier and dog on said bearing, one of said stops being subject to contact with said appendage so as to enable the wheel to be arrested and held by the joint action of this stop and the appendage and body of the dog, and this stop being part of a stop device which is loosely mounted on its support and movable slightly from its normal position when it is driven by force acting in the direction of that applied to the stop by the wheel, the shock absorbing spring being connected to this stop device and to the frame of the machine and tending to keep the stop device in its normal position on its support, and the dog rocking device being arranged to act on the dog so as to turn it on its own pivotal axis.
14. In an escapement comprising a toothed wheel and means tending constantly to turn it in one direction, the combination with the wheel of an angularly movable dog carrier, a dog and an appendage fast together, a stop device, a shock absorbing spring, and a key actuated dog rocking device, the dog carrier being mounted on a bearing that is coaxial with the wheel and being subjected to stress from a spring that tends constantly to turn it in a direction opposite to that in which the wheel steps, the dog being supported by the dog carrier and having a distinct pivotal axis and being subjected to stress from a spring which tends to keep the dog at rest on its own pivotal axis and the appendage of the dog extending farther from the axis of the wheel than do the teeth, the stop device including a wheel arresting stop and a snap-limiting stop, and being loosely mounted on its support and movable slightly from its normal position when it is driven by force acting in the direction of that applied by the wheel to the wheel arresting stop, each of 130

- the stops being subject to contact with the appendage and coöperative with it in limiting angular movements of the dog, the shock absorbing spring being connected to the stop device and to the frame of the machine and tending to keep the stop device in its normal position on its support, and the dog rocking device being arranged to act on the dog so as to turn it on its own pivotal axis.
10. 15. In an escapement comprising a toothed wheel and means tending constantly to turn it in one direction, the combination with the wheel of an angularly movable dog carrier, a dog and an appendage fast together, two stops, a shock absorbing spring, and a key actuated dog rocking device including an angularly movable arm, the dog carrier being mounted on a bearing that is coaxial with the wheel and being subjected to stress from a spring that tends constantly to turn it in the direction opposite to that in which the wheel steps, the dog being supported by the dog carrier and having a distinct pivotal axis and being subjected to stress from a spring which tends to keep the dog at rest on its own pivotal axis and the appendage of the dog extending farther from the axis of the wheel than do the teeth, the stops being arranged to limit angular movements of the dog carrier and dog on said bearing, one of said stops being subject to contact with said appendage so as to enable the wheel to be arrested and held by the joint action of the stop and the appendage and body of the dog, and this stop being part of a stop device which is loosely mounted on the angularly movable arm of the dog rocking device and capable of sliding thereon when it is driven by force acting in the direction of that applied to the stop by the wheel, the shock absorbing spring being connected to this stop device and to the frame of the machine and tending to keep the stop device in its normal position on its support, and the dog rocking device being arranged to act on the dog so as to turn it on its own pivotal axis.
16. In an escapement comprising a toothed wheel and means tending constantly to turn it in one direction, the combination with the wheel of an angularly movable dog carrier, a dog and an appendage fast together, and a key actuated device forming a dog rocking device and stop device having two stops, the dog carrier being mounted on a bearing that is coaxial with the wheel and being subjected to stress from a spring that tends constantly to turn it in the direction opposite to that in which the wheel steps, the dog being supported by the dog carrier and having a distinct pivotal axis and being subjected to stress from a spring which tends to keep the dog at rest on its own pivotal axis, and the appendage of the dog extending farther from the axis of the wheel than

do the teeth, the key actuated device having three walls, which bound on three sides a space into which said appendage extends, two of these walls forming said stops and being subject to contact with said appendage so as to limit angular movements of the dog carrier and dog on said bearing, and the other wall being movable against said appendage so as to turn the dog on its own pivotal axis.

17. In an escapement comprising a toothed wheel and means tending constantly to turn it in one direction, the combination with the wheel of an angularly movable dog carrier, a dog and an appendage fast together, two stops, and a key actuated dog rocking device, the dog carrier being mounted on a bearing that is coaxial with the wheel and being subjected to stress from a spring that tends constantly to turn it in the direction opposite to that in which the wheel steps, the dog being supported by the dog carrier and having a distinct pivotal axis and being subjected to stress from a spring which tends to keep the dog at rest on its own pivotal axis, and the appendage of the dog extending farther from the axis of the wheel than do the teeth, the stops being arranged to limit angular movements of the dog carrier and dog on said bearing, one of the stops being subject to contact with said appendage so as to enable the wheel to be arrested and held by the joint action of this stop and the appendage and body of the dog, and the dog rocking device including a slide subjected to stress from a spring which tends to hold the slide in its normal position on said device, the slide being movable against said appendage so as to turn the dog on its own pivotal axis when the dog rocking device is actuated, and said slide having a shoulder behind which said appendage may pass when the dog is disengaged from the wheel, and on which said appendage may act so as to move the slide when the dog, driven by the wheel, carries said appendage to the wheel arresting stop.

18. In an escapement comprising a toothed wheel and means tending constantly to turn it in one direction, the combination with the wheel of an angularly movable dog carrier, a dog and an appendage fast together, two stops, and a key actuated dog rocking device, the dog carrier being mounted on a bearing that is coaxial with the wheel and being subjected to stress from a spring that tends constantly to turn it in the direction opposite to that in which the wheel steps, the dog being supported by the dog carrier and having a distinct pivotal axis and being subjected to stress from a spring which tends to keep the dog at rest on its own pivotal axis, and the appendage of the dog extending farther from the axis of the wheel than

- of the wheel than do the teeth, the stops being arranged to limit angular movements of the dog carrier and dog on said bearing, one of the stops being subject to contact with 5 said appendage so as to enable the wheel to be arrested and held by the joint action of this stop and the appendage and body of the dog, and the dog rocking device including an angularly movable arm and a slide mounted 10 on said arm and subjected to stress from a spring which tends to hold the slide in its normal position on said arm, the slide being movable against said appendage so as to turn the dog on its own pivotal axis when the 15 dog rocking device is actuated, and said slide having a shoulder behind which said appendage may pass when the dog is disengaged from the wheel, and on which said appendage may act so as to move the slide 20 when the dog, driven by the wheel, carries said appendage to the wheel arresting stop.
19. In an escapement comprising the mechanism specified in claim 1, the combination with such mechanism of a holding dog 25 attached to the dog rocking device.
20. In an escapement comprising the mechanism specified in claim 9, the combination with such mechanism of a holding dog attached to the dog rocking device.
- 30 21. In an escapement comprising the mechanism specified in claim 10, the combination with such mechanism of a holding dog attached to the dog rocking device.
22. In an escapement comprising the mechanism specified in claim 11, the combination with such mechanism of a holding dog 35 attached to said rocking arm.
23. In an escapement comprising the mechanism specified in claim 12, the combination with such mechanism of a holding dog 40 attached to said rocking arm.
24. In an escapement, the combination of a toothed wheel subject to the action of means which tends constantly to turn it in 45 one direction, an elongated stepping dog movable transversely of the path of the teeth of the wheel, a dog rocking device arranged to act on this dog to move it from said path, and means to limit the movements of the 50 dog in the direction in which it steps, the elongation of the dog forming a device which extends nearly to and overlaps the back of the first tooth behind which the dog rests when it is fully engaged by the wheel.
- 55 25. In an escapement, the combination of a toothed wheel subject to the action of means which tends constantly to turn it in one direction, an angularly movable dog carrier mounted on a bearing coaxial with the 60 wheel, an elongated stepping dog attached to said carrier and movable transversely of the path of the teeth of the wheel, a dog rocking device arranged to act on this dog to force it from said path, and means to 65 limit the angular movements of the dog
- on said bearing, the elongation of the dog extending nearly to and overlapping the back of the first tooth behind which the dog rests, when it is fully engaged by the wheel and having a cylindrical surface 70 which is coaxial with the wheel and faces and lies close to an interdental portion of its periphery when the dog is in the path of the teeth.
26. In an escapement comprising the 75 mechanism specified in claim 24, the combination with such mechanism, of a holding dog attached to the dog rocking device.
27. In an escapement comprising the mechanism specified in claim 25, the combination with such mechanism, of a holding dog 80 attached to the dog rocking device.
28. In an escapement comprising a toothed wheel and means tending constantly to turn it in one direction, the combination with the 85 wheel of, a dog carrier, a dog, two stops and a key actuated dog rocking device, the dog carrier being movable in one direction by a spring and in the opposite direction by force exerted on the dog by the wheel, the 90 dog being attached to the dog carrier and having a pivotal axis which is in a plane perpendicular to the axis of the wheel and being subjected to stress from a spring which tends to keep the dog at rest on its 95 pivotal axis, the stops being arranged to limit the common movements of the dog carrier and dog, and the dog rocking device being arranged to act on the dog so as to turn it on its pivotal axis. 100
29. In an escapement comprising a toothed wheel and means tending constantly to turn it in one direction, the combination with the wheel, of a dog carrier, a dog and an appendage fast together, two stops, and a key 105 actuated dog rocking device, the dog carrier being movable in one direction by a spring and in the opposite direction by force exerted on the dog by the wheel, the dog being attached to the dog carrier and having a 110 pivotal axis which is in a plane perpendicular to the axis of the wheel and being subjected to stress from a spring which tends to keep the dog at rest on its pivotal axis, the stops being arranged to limit the 115 common movements of the dog carrier and dog, and the dog rocking device being arranged to act on the appendage of the dog so as to turn the dog on its pivotal axis.
30. In an escapement mechanism, a toothed 120 escape wheel, a dog carrier, a dog thereon movable transversely of the axis of said wheel and also longitudinally of said axis, and key actuated means for moving said dog independently of its carrier in the last 125 mentioned direction, said dog carrier and said key actuated means being mounted independently of each other.
31. In an escapement mechanism, a toothed escape-wheel, a dog carrier, a dog thereon 130

movable transversely of the axis of said wheel and also longitudinally of said axis, and key actuated means for moving said dog independently of its carrier in the last 5 mentioned direction, the dog carrier being mounted to turn angularly about the axis of the escape-wheel, and the key actuated means being mounted in the framework.

32. In an escapement, the combination of 10 a toothed wheel, a dog carrier, an actuating spring connected to the dog carrier, a spring pressed dog mounted on and movable relatively to the dog carrier, and key actuated dog moving means, the dog being normally 15 engaged with the wheel and the key actu-

ated means being operative on the dog to disengage it from the wheel while the dog carrier is at rest, and the dog carrier being movable to and fro at each operation of the escapement by said actuating spring and by 20 force transmitted to the dog carrier from the wheel respectively.

Signed at the borough of Manhattan, city of New York, in the county of New York and State of New York this 15th day 25 of May, A. D. 1920.

DANIEL A. CARPENTER.
